UNITED STATES PATENT OFFICE.

ANTON JONCHA, OF MELROSE PARK, ILLINOIS, ASSIGNOR TO OIL PRODUCTS APPLIANCE COMPANY, OF MAYWOOD, ILLINOIS, A CORPORATION OF ILLINOIS.

MEASURING PUMP.

Application filed October 19, 1923. Serial No. 669,561.

To all whom it may concern:

Be it known that I, ANTON JONCHA, a citizen of the United States, residing at Melrose Park, in the county of Cook and State of Illinois, have invented certain new and useful Improvements in Measuring Pumps, of which the following is a specification.

This invention relates to measuring pumps, for delivering a predetermined quantity of liquid at each upward stroke of the pump rod. In carrying out the invention I provide a rack on the pump rod and mechanism associated with the rack for moving it in both directions by a continuous rotation of the crank handle, this mechanism including a clutch member and means for automatically shifting said member at predetermined points in the upward travel of the pump rod and at the end of the downward stroke of the same. The invention comprises novel means for moving the clutch member to cause a reversal of the pump stroke, and novel means for timing the operation of the clutch-moving means to movements of the pump rod whereby the upward movement of the rod will be stopped when an exact predetermined amount of liquid has been delivered. The invention also includes means whereby the quantity of liquid delivered at each stroke of the pump may be varied, as desired, and means for locking the clutch member in neutral position so that the pump cannot be used by unauthorized persons. The invention also comprises various details of construction hereinafter more particularly described.

In the accompanying drawing which illustrates the invention,

Fig. 1 is a side elevation of the pump, partly broken away, looking from left to right in Fig. 2, the gear housing and part of the rack bar being shown in vertical section;

Fig. 2 is a front elevation of the pump, partly broken away;

Fig. 3 is a section on the line 3-3 of Fig. 2;

Fig. 4 is a section on the line 4-4 of Fig. 3;

Fig. 5 is a section on the line 5-5 of Fig. 3;

Fig. 6 is a section on the line 6-6 of Fig. 3;

Fig. 7 is a front elevation of the lower part of the gear housing, partly in section,

showing the locking mechanism for the clutch wheel;

Fig. 8 is a section on the line 8-8 of Fig. 7;

Fig. 9 is a rear perspective view of the rack bar and various operating parts;

Fig. 10 is a detail view, looking from left to right in Fig. 9, illustrating the action of the parts for shifting the clutch wheel, the cam actuated by the pump being shown in 65 the position where it has just passed over the center of the spring plunger, during the upward movement of the pump rod; and,

Fig. 11 is a similar view showing the positions of the parts after the cam and clutch-70 shifting lever have both passed the centers of the plungers which bear against them and the clutch wheel has been shifted.

Referring to Figs. 1 and 2 of the drawing, *a* represents the base of a pump upon which 75 is mounted a column *b*, and on the upper end of the column is secured a gear casing *c*. The gear casing is partially supported and steadied by the delivery pipe *d* of the pump, which is clamped within a sleeve 1 on the 80 casing by a set screw 2. The pump rod 3 carries a three-sided rack *e* which is engaged by a pinion 4, which pinion is keyed to a countershaft 5, journaled in suitable bearings in the sides of the casing. The 85 pinion 4 also meshes with an idle pinion 7, mounted upon a stud 8, and the idle pinion meshes with a pinion 9, mounted to turn upon a crank shaft 10. The countershaft also carries a relatively large gear 11, which 90 is secured to it, and this large gear meshes with a pinion 12 mounted to turn upon the crank shaft 10. The hubs of the pinions 9 and 12 are spaced apart and provided with clutch teeth 13, and upon a squared part of 95 the shaft 10, between these hubs, is mounted a clutch wheel *f*, having teeth 14 on its opposite sides, as shown, for engaging the teeth on the hubs of the pinions 9 and 12.

When the clutch wheel is in engagement 100 with the pinion 12 and the crank shaft is turned by the handle 10^a, in the clockwise direction, the pinion 12 will be turned with said shaft and this will drive the gear 11 and pinion 4 in the direction to raise the 105 rack and pump rod. When the clutch engages the pinion 9 and the crank shaft is turned in the clockwise direction, the pinion 9 will be turned and will drive the idle gear 7 and pinion 4 in the direction to lower the 110

rack and pump rod. When the pinion 9 is in engagement with the clutch wheel, the pinion 12 turns loosely on the crank shaft, and when the pinion 12 is driven by the clutch, the pinion 9 turns loosely on the crank shaft. As the pinion 12 drives the pump rod and rack through the large intermediate gear 11 while the pinion 9 drives it through a smaller gear or pinion 7, the upward movement of the rack and pump rod will be slower than the downward or return movement.

In order that the pump may deliver a measured quantity of liquid on its upward stroke, I provide means for automatically shafting the clutch wheel from engagement with the pinion 12 into engagement with the pinion 9, after the pump rod has made a given upward movement; and after the clutch wheel has been shifted the continued rotation of the crank shaft in the same direction causes the rack and pump rod to descend to its lowermost position, where the clutch wheel is again automatically shifted so that the rack and rod will again move upward to deliver another measured quantity of liquid if the hand crank is turned in the same direction as before. I also provide means for controlling the clutch shifting mechanism so as to shorten or lengthen the stroke of the pump, to deliver different measured quantities of liquid such as quarts, half-gallons, and gallons, As shown most clearly in Fig. 9 of the drawing, upon the opposing sides of the rack bar are arranged stops 15 and 16, and below the latter stop is a stop 17 which extends from side to side of the bar. Upon the rod 18 which extends transversely in the gear casing at the rear of the rack is arranged a tappet lever *g*, which is secured to a sleeve 19, this sleeve being slidably and rotatably mounted upon the rod. The forward arm 20 of the tappet lever projects into the space between the opposing sides of the rack and the sleeve may be adjusted to bring said arm into the path of movement of any one of the stops 15, 16, or 17. As shown in Fig. 9, said arm is in the path of movement of the stop 15. For adjusting the tappet lever, I provide a shaft 21 which extends forwardly through the casing and is provided at its rear end with an arm or lever 22 which engages a pocket 23 on the sleeve. On the forward end of the shaft 21, outside of the casing, is arranged an index arm or pointer 24 which is movable to different points on an index plate 25, arranged on the front of the casing. This index plate has marks 15^a, 16^a, and 17^a, to indicate different measured quantities of liquid which the pump will deliver when the index arm is set in the different positions. Thus, when the index arm is set opposite the point 15^a, the tappet lever will be in line with the uppermost stop 15

on the rack and the tappet lever will be rocked to cause the shifting of the gears, by the means hereinafter described, after a relatively short upward movement of the rack and pump rod and the delivery of a relatively small quantity of liquid. If the index arm is set opposite the central index mark 17^a, the tappet lever will be shifted to a position centrally between the sides of the rack, and after a relatively long movement of the rack bar, the central portion of the stop 17 will engage and rock the tappet lever to cause a reversal of the pump rod. If the index arm is moved to a point opposite the mark 16^a, the tappet lever will be shifted into the path of movement of the stop 16, which is intermediate the stops 15 and 17, and it will rock the tappet lever after the pump rod has made an upward movement intermediate the movements controlled by the stops 15 and 17.

The rear arm 20^a of the tappet lever projects over the rear arm 26 of a tripping lever *h* which is centrally mounted to rock on a rod or bar 27, which extends transversely of the gear casing below the bar 18. Upon this tripping lever are three vertically adjustable stops, 15^b, 16^b, and 17^b, arranged so that when the forward end of the tappet lever is in the path of movement of the stop 15 on the rack, its rear end will extend over the stop 15^b; and similarly when the forward end of the tappet lever is arranged in the path of movement of the stop 16, or of the stop 17, the rear end of said lever will be over the stop 16^b or 17^b. These adjustable stops are provided in order that the tripping lever may perform its function of causing the clutch gear to shift at an exact point in the upward movement of the pump rod, when the proper quantity of liquid has been delivered. An adjustable stop 28 is arranged beneath the rear end of the tripping lever for limiting the rocking movement of the latter.

The forward arm 26^a of the tripping lever extends beneath an arm 29 which projects laterally from a heart-shaped cam *j*, which has an oscillating movement upon a shaft 30 which extends forwardly through the casing and is provided on its outer end with a suitable handle 31. The cam *j* is integral with a sleeve 32 which is journaled on said shaft and this sleeve has at one end a lug 32^a which interlocks with a similar lug 33^a on a sleeve 33, which is secured to the shaft by a pin 34. The lugs 32^a and 33^a are less than 180° in length so as to provide a lost motion connection between the sleeve 32 and 33 and therefore also between the sleeve 32 and the shaft 30 on which the sleeve 33 is secured. The sleeve 33 carries a clutch-shifting arm *h* which extends into the space between flanges 35 on the clutch wheel. An off-center device *o* is provided for pre-

venting the clutch shifting arm from occupying a neutral position and for causing said arm to hold the clutch wheel in engagement with the teeth on one or the other of the 5 pinions 9 or 12. This device comprises a plunger 36, having a wedge-shaped end and impelled by a spring 37 against the clutch shifting arm, which has a central radial ridge 38 between two oppositely sloping 10 cam faces 39 which are adapted to be engaged by the wedge-shaped end of the plunger. Beneath the heart-shaped cam *j* is arranged an off-center device *p*, similar to the device *o* but having a spring 40 which is 15 much stronger than the spring 37. This latter off-center device comprises the spring 40 and the plunger 41 which is pressed upwardly by said spring against the cam *j*. The end of the plunger 41 is wedge-shaped, 20 as shown.

When the pump rod and rack are moving upward and before any of the stops on the rack bar have engaged the tappet lever, the parts are in the position shown in Fig. 9, with 25 the clutch wheel engaging the pinion 12, indicated in dotted lines in said figure. When the stop on the rack bar, which is in line with the tappet lever, engages and rocks the latter, said lever causes the tripping lever 29 to rock and the latter in turn moves the arm 29 of the heart-shaped cam upward and the cam causes the plunger 41 of the device *p* to be depressed and the pointed end of the cam passes over the end of the plunger, as shown 35 in Fig. 10. During this movement of the cam, which is relatively slow, the clutch wheel *f* is not moved owing to the lost motion connection between the sleeve of the cam and the sleeve of the gear shifting 40 lever and to the fact that the off-center device *o* presses the clutch shifting lever in the direction to hold the clutch wheel in engagement with the pinion 12. After the 45 point of the cam has passed beyond the center of the plunger 41 a sufficient distance to take up the lost motion between the cam sleeve and the sleeve of the clutch shifting lever, as shown in Fig. 10, the pressure of the spring 40 against the plunger 41 causes the latter to rock the cam and the latter turns the clutch arm *k*, causing the clutch wheel to be quickly disengaged from the pinion 12 and moved into engagement with the pinion 9. As the clutch-shifting lever 55 passes its central position, the cam surface at one side of the radial ridge 38 on said lever presses the plunger 36 backward against the tension of the spring 37, and the plunger then springs outward and bears 60 against the cam surface on the opposite side of the radial ridge to hold the clutch in engagement with the pinion 9 while the cam *j* is being moved to shift the clutch in the reverse direction at the end of the downward stroke of the pump rod. When the

clutch wheel is shifted from the pinion 12 to the pinion 9, the upward movement of the rack and pump rod ceases, and if the movement of the crank shaft is continued the pump rod and rack will be driven downward. At the lower end of the stroke of the pump, an adjustable stop 42 on the side of the pump rack, near its upper end, bears upon the arm 29 of the cam *j* (which is then in the raised position shown in Fig. 11), and this causes the cam to rock in the reverse direction. In this rocking movement it depresses the plunger 41 and rides over the pointed end of the plunger, after which the plunger springs upwardly, causing the cam to continue its movement and actuate the clutch lever in the direction to shift the clutch pinion into engagement with the pinion 12, and the off-center device *o* is pressed backward by the clutch shifting lever and then springs forward to press said lever in the direction to hold the clutch wheel in engagement with the pinion 12.

By adjusting the adjustable stops 15^b, 16^b, 17^b, upward or downward, the time in the stroke of the pump at which the cam will be carried over the center of the plunger 41, to reverse the gearing, may be accurately determined. By properly setting the adjustable stops, the exact measurement of liquid 95 may be delivered by the pump to correspond with the quantities indicated by the several points or marks on the index plate.

In filling tanks from the pumps, it happens frequently that the tank will be completely filled before the pump has finished its upward stroke. For that reason it is desirable to have means for reversing the gearing at any point in the stroke of the pump. This may be accomplished by turning the 105 shaft 30 by means of the handle 31 so as to cause the clutch lever *k* to move the clutch wheel *f* out of engagement with the pinion 12 and into engagement with the pinion 9. By thus turning the shaft 30, the cam *j* will 110 be thrown past the end of the plunger 41 and the plunger, as before described, will spring upwardly on the opposite side of the cam and the clutch wheel will then be held in engagement with the pinion 9 by the off-center device *o*. The operation of the hand crank in the clockwise direction will then 115 carry the rack and pump rod to its lowest position, when the stop 42 will engage the arm 29 on the cam and cause the shifting of the clutch wheel as before described.

When the pump is not in active use, it is desirable to lock it so that it cannot be operated by unauthorized persons. For this purpose, I provide a device for centering the clutch wheel between the pinions 9 and 12 and means for locking this device. The centering device comprises a shaft 43 which extends through the front of the casing and is provided with a handle 44, and on the 120 130

inner end of this shaft is arranged a flat head 45, which lies within the space between the flanges 35 of the clutch wheel and is adapted to extend practically from one flange to the other, as shown in Fig. 8, when the handle 44 is in one position. When the handle is turned 90° from the position shown in Fig. 8, the head will lie parallel with the flanges, as shown in Fig. 3, and midway between them so as to permit the wheel to be shifted. To lock the clutch wheel, the head is turned by means of the handle to the position shown in Fig. 8, and in this position the clutch wheel cannot be moved into engagement with either of the adjacent pinions. The shaft 43 may be locked with the head in this last mentioned position by means of the key-controlled lock 46, having a bolt 47, adapted to engage a recess in a lug 48, which is secured to the shaft 43.

It is believed that the operation of the pump will be clear from the foregoing, without further description.

What I claim is:

- 25 1. In a measuring pump, the combination with the pump rod, a rack thereon, a drive shaft and reversible gearing connecting the drive shaft with the rack including a clutch member, of means for shifting said member comprising a stop movable with the rack, a tappet lever adapted to be rocked by said stop during the upward movement of the rack, a tripping lever mounted independently of the tappet lever and adapted to be engaged and rocked by the tappet lever, a spring actuated off-center device movable by the tripping lever, and an arm movable by said device and engaging the clutch member.
- 30 2. In a measuring pump, the combination with the pump rod, a rack thereon, a drive shaft and reversible gearing connecting the drive shaft with the rack including a clutch member, of means for shifting said member comprising a stop movable with the rack, a tappet lever adapted to be rocked by said stop during the upward movement of the rack, a tripping lever mounted independently of the tappet lever and adapted to be engaged and rocked by the tappet lever, a spring actuated off-center device movable by the tripping lever, and an arm having a lost-motion connection with said device and movable by said device, means for varying the extent of movement of the tripping lever, a spring actuated off-center device movable by the tripping lever, and an arm movable by said device and engaging the clutch member.
- 35 3. In a measuring pump, the combination with the pump rod, a rack thereon, a drive shaft and reversible gearing connecting the drive shaft with the rack including a clutch member, of means for shifting said member comprising a stop movable with the rack, a tappet lever adapted to be rocked by said stop during the upward movement of the rack, a tripping lever mounted independently of the tappet lever and adapted to be rocked by the tappet lever, an adjustable

stop on the tripping lever adapted to be engaged by the tappet lever, a spring actuated off-center device movable by the tripping lever, and an arm movable by said device and engaging the clutch member. 70

4. In a measuring pump, the combination with the pump rod, a rack thereon, a drive shaft and reversible gearing connecting the drive shaft with the rack including a clutch member, a plurality of stops movable with the rack, a tappet lever, manually operable means for setting the tappet lever in the path of movement of any one of said stops, a tripping lever adapted to be rocked by the tappet lever, and means controlled by the 75 movement of the tripping lever for shifting the clutch member.

5. In a measuring pump, the combination with the pump rod, a rack thereon, a drive shaft and reversible gearing connecting the drive shaft with the rack including a clutch member, of means for shifting said member comprising a plurality of stops movable with the rack, a tappet lever, manually operable means for setting the tappet lever 80 in the path of movement of any one of said stops, a tripping lever having a plurality of adjustable stops adapted to be separately engaged by the tappet lever in its different set positions, and means controlled by the 85 movement of the tripping lever for shifting the clutch member.

6. In a measuring pump, the combination with the pump rod, a rack thereon, a drive shaft and reversible gearing connecting the drive shaft with the rack including a clutch member, of means for shifting said member comprising a stop movable with the rack, a tappet lever adapted to be rocked by said stop during the upward movement of the 90 rack, a tripping lever adapted to be rocked by the tappet lever, a spring actuated off-center device movable by the tripping lever, and an arm having a lost-motion connection with said device and movable by said device, 95 said arm engaging the clutch member.

7. In a measuring pump, the combination with the pump rod, a rack thereon, a drive shaft and reversible gearing connecting the drive shaft with the rack including a clutch member, of means for shifting said member comprising a stop movable with the rack, a tappet lever adapted to be rocked by said stop during the upward movement of the rack, a tripping lever adapted to be rocked by the tappet lever, a spring actuated off-center device movable by the tripping lever, an arm having a lost-motion connection with said device and movable by said device, said arm engaging the clutch 110 member, and a spring-actuated off-center device engaging said arm.

8. In a measuring pump, the combination with the pump rod, a rack thereon, a drive shaft and reversible gearing connecting the 115

drive shaft with the rack including a clutch member, of means for shifting said member comprising a stop movable with the rack, a tappet lever adapted to be rocked by said stop during the upward movement of the rack, a manually operable shaft, an arm secured thereon for moving the clutch member, a spring-actuated off-center device for moving said latter shaft comprising a part having a lost-motion connection with the same, and means operated by the tappet lever for moving said part against the action of its spring.

9. In a measuring pump, the combination with the pump rod, a rack thereon, a drive shaft and reversible gearing connecting the drive shaft with the rack including a clutch member, of means for shifting said member comprising a stop movable with the rack, a tappet lever adapted to be rocked by said stop during the upward movement of the rack, a manually operable shaft, an arm secured thereon for moving the clutch member, a spring-actuated off-center device for moving said latter shaft comprising a part having a lost-motion connection with the same, and a tripping lever interposed between said tappet lever and said part for moving said part against the action of its spring.

10. In a measuring pump, the combination with the pump rod, a rack thereon, a drive shaft and reversible gearing connecting the drive shaft with the rack including a clutch member, of means for shifting said member comprising a stop movable with the rack, a tappet lever adapted to be rocked by said stop during the upward movement of the rack, a manually operable shaft, an arm thereon engaging the clutch member, a heart cam on the latter shaft and having a lost-motion connection therewith, a spring-pressed plunger engaging the cam, and means movable by the tappet lever for rocking said cam.

11. In a measuring pump, the combination with the pump rod, a rack thereon, a drive shaft and reversible gearing connecting the drive shaft with the rack including a clutch member, of means for shifting said member comprising a stop movable with the rack, a tappet lever adapted to be

rocked by said stop during the upward movement of the rack, a manually operable shaft, an arm thereon engaging the clutch member, a heart cam on the latter shaft and having a lost-motion connection therewith, said cam having a laterally projecting arm, a tripping lever movable by the tappet lever and having an arm adapted to engage the arm on the cam to rock the latter when the rack moves upwardly.

12. In a measuring pump, the combination with the pump rod, a rack thereon, a drive shaft and reversible gearing connecting the drive shaft with the rack including a clutch member, of means for shifting said member comprising a stop movable with the rack, a tappet lever adapted to be rocked by said stop during the upward movement of the rack, a manually operable shaft, an arm thereon engaging the clutch member, a heart cam on the latter shaft and having a lost-motion connection therewith, a tripping lever movable by the tappet lever and adapted to rock the cam in one direction when the rack moves upwardly, and a stop, movable with the rack, adapted to rock said cam in the opposite direction at the end of the lowering movement of the rack.

13. In a measuring pump, the combination with the pump rod, a rack thereon, a drive shaft and reversible gearing connecting the drive shaft with the rack and including a clutch wheel slidably mounted on the shaft and having spaced flanges, of means for locking said wheel in neutral position comprising a part adapted to engage said flanges.

14. In a measuring pump, the combination with the pump rod, a rack thereon, a drive shaft and reversible gearing connecting the drive shaft with the rack and including a clutch wheel slidably mounted on the shaft and having spaced flanges, of means for locking said wheel in neutral position comprising a rotatably mounted shaft having a flat head extending into the space between said flanges and a lock for locking said shaft against rotation.

In testimony whereof I hereunto affix my signature.

ANTON JONCHA.
